UNITED STATES PATENT OFFICE.

HARRISON TAYLOR CRONK, OF NEW YORK, N. Y., ASSIGNOR TO CRONK-SALTER COMPANY, OF NEW YORK, N. Y., A CORPORATION OF NEW YORK.

TOILET-COMPARTMENT.

1,265,619.

Specification of Letters Patent.

Patented May 7, 1918.

Application filed January 10, 1913. Serial No. 741,301.

To all whom it may concern:

Be it known that HARRISON TAYLOR CRONK, of the city, county, and State of New York, and being a citizen of the United States, has 5 invented a certain new and useful Improvement in Toilet-Compartments, of which the following is a full, clear, and exact description, such as will enable others skilled in the art to which it appertains to make and to 10 use the same, reference being had to the accompanying drawings, which illustrate the preferred form of the invention, though it is to be understood that the invention is not limited to the exact details of construction 15 shown and described, as it is obvious that various modifications thereof will occur to persons skilled in the art.

My invention relates to a toilet compartment on railroad cars and to the disposition 20 and arrangement of the elements thereof.

The primary object of my invention is to preserve as far as possible the structural elements in a conventional form of passenger car, and at the same time dispose a removable 25 refuse toilet tank therein so as not to disfigure the normal appearance of the car, and to prevent freezing of the contents of the tank.

My invention has for another object the 30 economical arrangement of hopper and tank, so that a tank of maximum height may be disposed within the outlines of the car, taking into consideration the limitations due to the regulation height of the hopper 35 above the floor of the toilet compartment.

It is a further object of my invention to provide a unitary receptacle so disposed relative to vertically spaced floors that it 40 may be used as the usual seating hopper or a urinal conveniently located for the user while the car is rocking.

It is a further object of my invention to utilize the braced end framing of the under-frame, and particularly the tension portion 45 of the center and side sills, to carry the heavy refuse tank, and

A still further object is to provide an arrangement whereby the tank can be placed into fixed position relative to the hopper by 50 inserting the same through a suitable opening in the car side.

These and further objects, together with

the construction and combination of parts, will be more fully described hereinafter and particularly set forth in the claims. 55

Reference is to be had to the accompanying drawings forming a part of this specification, in which similar characters of reference indicate corresponding parts in all the views, and in which— 60

Figure 1 is a side elevation of the end portion of a railroad car, showing the external appearance of the same when constructed to contain my invention.

Fig. 2 is a similar view showing a portion 65 of the side sheeting broken away from a wood and steel car to show the tank and hopper in position in the toilet compartment, and showing the tank and portions of the car in section on the line 2—2 of Fig. 3. 70

Fig. 3 is a horizontal sectional view, taken on a plane indicated by the line 3—3 of Fig. 2, looking down on the hopper and tank, and

Fig. 4 is a vertical transverse section taken on a plane indicated by the line 4—4 of 75 Fig. 3.

Described more in detail I have shown a conventional form of passenger car, including a body portion A and trucks B. The carbody includes the conventional elements 80 going to make up the usual steel under-frame, and in the drawings there is shown a side sill C, end sill D, corner post E and car side girder plate F, the side sill C and girder plate F united by the vertical and diagonal 85 struts G, co-acting to form the car side framing, which framing carries the wooden or steel side sheeting H and inner lining I.

A portion of the interior of the car is divided off by partitions J to form a conventional toilet compartment K. Having their ends resting on the side sills and also supported by the center sill (not shown) are the sleepers L, carrying the usual floor M. 90

Within this compartment is disposed the removable refuse tank N and hopper P, connected by means of a trap Q and including a venting outlet R. 95

As this tank is positioned above the trucks, it is necessary to insert the same through an 100 opening T in the car side, and so as not to interfere with the side sills, the opening must be above the same and preferably between the side sills C and side girder

F. One or two of the struts G can be omitted at this place without materially affecting the side framing, and in order to utilize the space occupied by the sleepers, the flooring between an end sleeper and the rear partition S of the compartment may be dropped so that one side rests directly on the side sill or on the frost-proof covering on the sill and the other rests on the center sills or 10 members in turn supported thereby. This dropped floor forms a recess or pocket in which fits the tank N so as to bring the inlet of the same into juxtaposition to the outlet of the hopper.

15 The hopper P differs from the conventional form of hoppers in that it is of a minimum height, practically, without a supporting stand. The hopper is only of a height sufficient to perform its functions so 20 as to allow more space for the tank. The hopper is supported in such a way as to bring the tank close up under the same, and, as shown, a pair of angled and spaced apart brackets 5 are suitably affixed by 25 means of bolts 6 to the rear wall of the compartment K, and have their lower ends formed into feet 7, fastened to the floor M. These feet are braced apart by the step 8, hereinafter more fully described, by means 30 of the integral outturned flanges 9 fastened to opposite transverse sides of the step 8. These brackets are so angled that they fit as closely to the tank as possible without interfering with the insertion or withdrawal 35 of the same. Suitably mounted, preferably in fixed position on these brackets, is the hopper P, the outlet of which is arranged in alinement with the inlet 10 of the tank, when the latter is in its fitted position in 40 the recessed floor.

The position of the inlet to this hopper relative to the floor forms one of the features of this invention. It is understood that the conventional seating height of a hopper is 45 about 17 inches from the floor, and on trains the same receptacle is used both as a hopper and as a urinal. When used as a urinal it is too low, and this disadvantage is exaggerated when the device is on a rocking 50 platform, such as a car in motion. In order to raise the hopper to urinal height and at the same time provide more room for the tank, the top of the hopper is placed about 27" from the floor M.

55 In order to permit its use as a hopper, the step or supplemental floor 8 is placed directly in front of the hopper, and is of such height as to bring the top of the hopper the conventional seating height of 17 60 inches from the top thereof, and while providing a support for the feet of the person sitting on the hopper is not too wide to prevent the user straddling the same when using the hopper as a urinal.

65 The opening T through the car side may

be closed by means of the sliding door U to meet the requirements of the Master Car Builders' Association, but, preferably, the outer end of the tank itself may constitute the closure, and especially in the case of all 70 steel cars the end of the tank may readily be constructed to simulate a part of the side sheeting, and in this case the tank may be held in place by some suitable locking means V.

75 In this application the term car side is being used synonymous with car end, and the end sills are the equivalent of the side sills.

What I claim is:

1. The combination with an underframe for passenger cars, a floor spaced above said underframe, a refuse tank resting directly on said underframe and having a side thereof of abutting said floor.

80 2. The combination with a toilet compartment having a tank receiving open top recess therein, a toilet hopper fixedly positioned in said compartment above said recess, and a tank fitting said recess and removable therefrom, said tank having an inlet adapted when the tank is in said recess to be in juxtaposition to the outlet of said hopper.

85 3. In a car toilet compartment, supporting sills, sleeper carried by said sills, an upper toilet compartment floor supported from said sleeper, a second tank supporting floor resting on said sills below said first mentioned floor, and a tank adapted to rest on said lower floor and abutting said upper floor whereby the tank within the car extends above and below a toilet floor.

90 4. In an inclosed toilet compartment, a bracket, a hopper supported on said bracket above the floor of the compartment, and a refuse tank disposed between the floor and hopper and beneath a portion of said bracket.

95 5. In a toilet having a floor and a refuse tank containing space, a fixed bracket adapted to extend from said floor above said space, a hopper supported from said bracket, and a step carried by the floor in front of said hopper and affixed to said bracket.

100 6. In a car, the combination with a car side having an opening therein, of a hopper within the car, a hopper-supporting open frame, a tank insertible through said opening into said frame, said frame fixed in position offset from the space occupied by the tank and means providing a communication between said hopper and tank.

115 7. In a car, the combination with a car side having an opening therein and a tank supporting floor within the car and adjacent the bottom of said opening, of means outlining a portion of a tank-space above the floor, said space being opposite said opening, said means including a hopper-supporting frame incompletely inclosing said space whereby 120

ready access may be obtained to the parts adjacent the tank space.

8. The combination with an open frame including spaced apart bracket and a hopper supported by said brackets, of a removable tank insertible within said frame and means providing a fluid connection between said tank and hopper.

In witness whereof I have hereunto set my hand in the presence of two witnesses. ¹⁰
HARRISON TAYLOR CRONK.
